FENCE MAKING MACHINE

Vernie L. Johnson, Wyoming, Minn.

Application June 28, 1937, Serial No. 150,800

14 Claims. (Cl. 140—32)

This invention relates to a machine for making fence of the type in which a multiplicity of pickets are interwoven with wires.

It is an object of this invention to provide a machine of this class with novel means for twisting the wires between the pickets whereby the power is applied more directly to the twisting members and greater speed may be attained than with the mechanisms heretofore provided for this purpose.

Another object is to provide a machine of this class with novel and more efficient means for automatically stopping the machine whenever a picket is not fed to proper position relative to the twisting mechanism.

Other objects will appear and be more fully pointed out in the following specification and claims.

Referring to the accompanying drawings:

Figure 1 is a plan view of my improved machine with a portion of the housing for the twisting mechanism broken away;

Fig. 2 is a longitudinal section taken on the line 2—2 of Fig. 1.

Figs. 3 and 4 are cross sections taken on the lines 3—3 and 4—4 of Fig. 2;

Fig. 5 is a detail, partially in vertical section, showing one of the wire twisting units;

Fig. 6 is a fragmentary side elevation with part of the frame broken away and showing particularly the driving connections for the automatic stop device and fence moving mechanism;

Fig. 7 is a vertical section through a portion of the stop mechanism;

Fig. 8 is a section taken on the line 8—8 of Fig. 7 and showing additional portions of the stop mechanism in side elevation;

Fig. 9 is a detail, plan view showing a portion of the stop mechanism, and

Fig. 10 is a detail, side elevation of one of the twisting heads, with one of the bearings shown in vertical section.

As best shown in Figs. 2 and 4, the fence formed by my machine comprises a multiplicity of pickets 11 extending in parallel, spaced relation to each other and bound together by wires 12 which are twisted together in the spaces between pickets. The number of pairs of wires employed may be varied, but it is common practice to provide five pairs for a fence of this type, as illustrated. The wires are preferably fed from overhead rolls and are guided in pairs around feeding wheels 13 (Figs. 1 and 2) whence they pass horizontally into axial passages 14 formed in shafts 15 and emerge from twisting heads 16 which are fixed on the shafts 15. As best shown in Fig. 10 each of the twisting heads is generally U-shaped to afford an opening 17 into which the pickets 11 are fed.

Twisting mechanism

The pairs of wires pass, as hereinbefore described, through the shafts 15 and are then twisted together so as to bind the pickets. The twisting of the wires is accomplished by turning the shafts 15 alternately in clockwise and counter-clockwise directions, a picket being threaded between the pairs of wires after each of the successive twisting operations. The shafts 15 extend in parallel relation to each other in a housing 18, and anti-friction bearings are provided for each shaft near its ends. The exterior surface of each shaft is screw threaded with a double thread, indicated by the numeral 19, and pins 20 engage the threads respectively at diametrically opposite points on the periphery of the shaft to impart rotary motion to the shaft. The pins 20 are fixed in bearing blocks 21 which are severally secured to a cross head or carriage member 22 extending across the machine and having its ends fastened to blocks 23 respectively. Crank pins 24 are integral with the blocks 23 and project from the housing 18. The blocks 23 are guided for straight line, reciprocating movement by rods 25 which are fixed at their ends in the housing 18. The housing 18 and its contents are supported on main frame members 26 and 27 of the machine. At opposite sides of the housing, connecting rods 28 are joined to the pins 24 respectively and are arranged to be operated by cranks 29 fixed on the ends respectively of a horizontal shaft 30.

By the described mechanism rotation of the shaft 30 is caused to impart reciprocating movement, longitudinally of the shafts 15, to the carriage member carrying the blocks 23 and pins 20. As best shown in Fig. 5, the threads 19 formed on each shaft 15 terminate in straight portions 19a which extend longitudinally of the shaft. The pins 20 move in these straight portions 19a to hold the shafts 15 against turning during a substantial portion of the cycle of operation. By this arrangement I cause the shafts 15 to dwell in proper position to receive the pickets in the openings 17 of the twisting heads 16 for a sufficient period of time at each end of the stroke of the member 22. In the machine illustrated, each of the threads 19 makes two and one-half complete revolutions, spirally around the shaft 15 to produce a corresponding number of turns in the fence wires. Considering any particular thread, it will be evident that its opposite ends terminate in straight portions 19a at opposite peripheries of the shaft.

To drive the shaft 30 a large gear 31 is fixed thereon and gears 32 and 33 (Fig. 2) drive the gear 31. The gear 32 is mounted on a shaft 34 and the gear 33 is fixed on a main drive shaft extending parallel to the shafts 31 and 34 and

arranged to be driven by power applied to a pulley 36. The gear ratio is such that the shaft 30 is driven at half the speed of the shaft 35 and the latter makes one revolution for each 5 picket that is woven into the fence.

The threaded shafts 15 and turning mechanism therefor are fully and properly lubricated at all times and, being enclosed in the housing 18, are efficiently protected against such friction as 10 is commonly caused by deposits of grit and other foreign matter on the bearing surfaces in other machines of this class. By my screw threaded arrangement of these shafts and cross head for turning them and causing them to dwell in the 15 picket receiving positions, power is applied more directly to each shaft than in other twisting mechanisms known to me. As a result of these features the entire machine may be speeded up so that the rate of making the fence is substantially increased. 20

Picket feeding mechanism

Mechanisms for feeding pickets to a machine of this class are well known in this art and are described herein only as a desirable accessory to the improvements claimed herein. As illustrated in Figs. 1 and 4, a table 37 is arranged at one side of the main frame of the machine to receive bundles of pickets and a pair of endless chains 38 are arranged on this table to advance the pickets successively and edgewise into the bite of feeding wheels 39 and 40. The wheel 39 has a knurled or otherwise roughened periphery which engages the pickets and is continuously driven by power supplied by a small electric motor 41 transmitted through belts 42 and 43 guided on suitable pulleys, one of which is fixed on a shaft 39a driving the wheel 39. The wheel 40 is freely revolvable on an arm 44 pivotally supported on a pin 45 and arranged to be actuated by a cam 46 engaging a roller 47 mounted on the arm 44. The cam 46 is fixed on an end of a shaft 48 which, as shown in Figs. 4 and 6, is rotated through a chain 49 and suitable sprocket wheels 50 and 51, the latter sprocket wheel being secured to the main drive shaft 35.

From the wheel 39 the pickets are fed longitudinally into the openings 17 in the twisting heads, being carried along the desired path by wheels 52 and 53 which are power driven by the motor 41 through the belt 42 and a belt 54. Spring pressed wheels 55 are arranged to press the pickets upward into engagement with the lower peripheries respectively of the wheels 52 and 53. By this mechanism each of the successive pickets is advanced longitudinally until its leading end strikes a movable head 56 of my improved mechanism for automatically stopping the machine in the event that a picket is not fully and properly fed 60 into the machine.

Automatic stop mechanism

This mechanism guards against the manufacture of fence which is defective by reason of non-uniformity in the positions of the pickets or containing pickets which are broken or shorter than the others. As best shown in Figs. 1 and 4, the head 56 is mounted on a housing 57 which is secured to the main frame member 27 in such position that the head 56 is struck by the successive pickets when they are fully and properly fed into the machine. The head 56 is movable in the housing 57 and is connected to a short shaft 58 in the same housing in such manner that the shaft is free to turn independently of the head

but moves longitudinally with the head. Integral with the shaft 58 is a lug 59 (Figs. 7 and 8) which is revolvable in a cam groove 60 in the housing 57 and arranged to strike and actuate a finger 61 mounted in the normal path of the lug. The finger 61 is secured to a shaft 62 which has a bearing in the housing 57. Fixed on the shaft 62 at the outer end of the housing is an arm 63 for operating a clutch, as hereinafter described. A dog 64 is mounted in the housing 57 on a pivot pin 65 and is arranged to be normally held by a spring 66 in the path of the lug 59 when the latter is moved longitudinally or to the left as seen in Fig. 7. This dog is formed to engage the lug 59 and momentarily retard its return to the right. Fixed on the outer end of the shaft 58 is a sprocket 67 adapted to be continuously driven in timed relation to the shaft 48 through a chain 68 and sprocket wheel 69 secured to the shaft 48 (Figs. 4 and 6). This driving mechanism rotates the shaft 58 one complete revolution for each picket that is woven into the fence.

The arm 63 is arranged to control a clutch 70 which is interposed between the main drive pulley 36 and the shaft 35. As best shown in Fig. 3, a clutch operating lever 71 projects downward from the clutch and is pivoted on a bracket 72 secured to the frame member 27. Joined to the lower end of the lever 71 is a link 73 extending across the machine in parallel relation to the shaft 35 and arranged to be actuated by a lever 74. This lever is pivoted on a bracket 75 at its lower end and its upper or free end may be manipulated to operate the clutch manually. The lever 74 is also arranged to be actuated by a spring-pressed rod 76 extending horizontally across the machine above the shaft 35, this rod being movable longitudinally in a fixed bearing 77. An end of the rod 76 projects laterally to engage the outer edge of the lever 74 and a compression spring 78 is coiled on the rod and confined between the bearing 77 and a collar 79 fixed on the rod. This spring 78 urges the rod 76 to the right as seen in Fig. 3. Toggle members 80 and 81 are connected to an end of the rod 76 which projects at the outer face of the frame member 27. As shown in detail in Figs. 8 and 9, one end of the member 81 is pivotally connected to the projecting end of the rod 76 and the other end of this toggle member is joined to the second toggle member 80. The latter has its outer end pivotally secured to a bracket 82 projecting from the frame member 27. A rod 83 is secured to the toggle member 81 and extends to the arm 63 to which it is joined in such a manner that when the finger 61 is actuated by the lug 59 on the shaft 58 the rod 83 is drawn to the left, as seen in Figs. 8 and 9, to draw the toggle members 80 and 81 out of alignment with each other and with the rod 76. This releases the rod 76 so that the latter under the force exerted by the spring 78 actuates the lever 74 to release the clutch.

As best shown in Fig. 9, a screw 81a is threaded in the toggle member 81 near its junction with the member 80 to abut against the bracket 82 and limit movement of the toggle members past dead center position. To urge the toggle members toward the aligned position, indicated in Fig. 9, wherein the rod 76 is held in its normal operating position, a small spring 81b is coiled about the pivot connecting member 80 to the bracket 82 and has laterally bent ends engaging the bracket and toggle respectively.

To insure immediate stopping of the machine when the clutch is disengaged from the pulley

36, I provide a brake member 84 which is keyed to the shaft 35 but movable longitudinally thereon to engage a fixed brake member 85 secured to the frame member 26. The brake member 84 is actuated by a lever 86 which is pivoted on a bracket 87 and connected to the rod 76, as best shown in Fig. 3.

In operation the shaft 58 is driven in timed relation to the picket feeding mechanism and as 10 the successive pickets strike the head 56 they actuate the shaft 58 and lug 59 to such position that the lug passes the finger 61 and is caught by the dog 64. This dog 64 guides the lug 59 to one side of the finger 61 until the latter has been 15 passed. Upon failure of a picket to strike the head 56 at the proper time, the rotating lug 58 actuates finger 61 and, through the shaft 62, arm 63 and rod 83, pulls the toggle members 80 and 81 out 20 of their aligned position shown in Fig. 9. When this occurs the spring 78 actuates the rod 76 to release the clutch and apply the brake simultaneously, thereby stopping the machine. Now 25 the defective or improperly positioned picket which caused the stop may be removed from the twisting heads and replaced or adjusted and the machine may be started by actuating the lever 74 to compress the spring 78 and return the toggle members 80 and 81 to their aligned position. This 30 simultaneously releases the brake and applies the power to the shaft 35 through the clutch 79.

As the machine operates at high speed, the pickets have substantial momentum as they strike the head 56 and have a tendency to rebound therefrom. Such rebound, in the absence 35 of the dog 64, would cause the shaft 58 to follow, with the result that the lug 59 would strike the finger 61 and thereby stop the machine even though the picket were properly delivered against the head 56. The cam groove 60 positively restores the shaft 58 to its normal position in the plane of the finger 61 during that portion of each cycle of operation when a picket is being fed into the twisting heads 16.

Fence delivery mechanism

45 After each picket has been fed into the openings 17 in the twisting heads 16 it is ejected therefrom, edgewise, by a plurality of arms 88 which project upward between the twisting heads 16 and are pivotally mounted on a horizontal shaft 89 (see Figs. 1, 2, 4 and 6). To actuate the arms 88, I provide a series of cams 90 secured to the shaft 35 and arranged to engage rollers 91 mounted on rods 92. One end of 50 each of the rods 92 is pivotally secured to one of the arms 88 and the arms are severally slidably in bearings in angle bars 93 extending across the machine and supported on the main frame members 26 and 27. A coiled spring 94 is 55 confined on each of the rods 92 and abuts against one of the bars 93 to retain the roller 91 in engagement with the periphery of the cam 90. These cams actuate the arms 88 simultaneously to remove the successive pickets from the twisting heads in proper timed relation to the twisting operation which immediately follows.

As hereinbefore described, the shafts 15 are 60 rotated to twist the pairs of wires between adjacent pickets and thereby form the fence. As 65 shown in Fig. 2, the continuous fence thus formed passes over toothed wheels 95. These wheels are mounted on a horizontal shaft 96 which may be turned in proper timed relation to the other mechanisms by any suitable means. 70 As shown in Figs. 1 and 6, the shaft 96 may

be turned by ratchet mechanism including a dog 97 mounted on one of the arms 88 and arranged to actuate a sprocket wheel 98 fixed on the shaft 96. From the periphery of the toothed wheels 95 the fence passes down beneath the lower peripheries of guide wheels 99 and thence to a reel (not shown) of any suitable or well known construction. 5

Having described my invention, what I claim as new and desire to protect by Letters Patent is: 10

1. A fence making machine comprising, a plurality of spaced, parallel shafts, wire twisting heads mounted on said shafts, means for feeding to each of said heads a pair of wires to be twisted, threads formed on said shafts, a carriage movable longitudinally of said shafts adjacent to the same, means on said carriage severally engaging the threads on said shafts and power-driven means for imparting reciprocating movement to said carriage to simultaneously 15 turn said shafts.

2. A fence making machine comprising, a plurality of spaced, parallel shafts, a wire twisting head mounted on an end of each of said shafts, 20 passages for pairs of wires to be twisted extending longitudinally through said shafts, threads formed on the peripheries of said shafts, a carriage movable longitudinally of said shafts, means mounted on said carriage to engage the threads on each of said shafts to turn the same 25 and power-driven means for imparting reciprocating movement to said carriage longitudinally of said shafts.

3. A fence making machine comprising, means for feeding pickets and wires thereto, a plurality 30 of spaced, parallel shafts, wire twisting heads mounted on said shafts and each engaging a pair of said wires, threads formed on said shafts, a carriage movable longitudinally of said shafts adjacent to the same, means on said carriage 35 severally engaging the threads on said shafts and power-driven means for imparting reciprocating movement to said carriage to simultaneously turn said shafts and twist said wires between pickets. 40

4. A fence making machine comprising, a plurality of spaced, parallel shafts, a wire twisting head secured to each of said shafts, means for feeding wires and pickets to said heads, threads formed on said shafts, a carriage movable longitudinally of said shafts, means on said carriage 45 severally engaging the threads on said shafts, for turning the same, means for moving pickets away from said heads and power-driven means for imparting reciprocating movement to said carriage to simultaneously turn said shafts and thereby bind the pickets together in a fence with the wires. 50

5. A fence making machine comprising, a plurality of spaced, parallel shafts, a wire twisting head secured to each of said shafts, means for feeding wires and pickets to said heads, threads formed on said shafts, each of said threads having a helical portion and a straight portion extending longitudinally of a shaft, a carriage 55 movable longitudinally of said shafts, means on said carriage severally engaging the threads on said shafts and power-driven means for imparting reciprocating movement to said carriage to simultaneously turn said shafts, the several 60 shafts being held in picket-receiving position by movement of said thread-engaging means in said straight portions of the threads. 65

6. A fence making machine comprising, a plurality of spaced, parallel shafts, a wire twisting 70

- head secured to each of said shafts, means for feeding wires and pickets to said heads, threads formed on said shafts, each of said threads having a helical portion and a straight portion 5 extending longitudinally of a shaft, a cross head movable longitudinally of said shafts, bearing blocks secured to said cross head and embracing said shafts respectively, a thread-engaging member projecting from each of said blocks and 10 power-driven means for imparting reciprocating movement to said cross head to simultaneously turn said shafts, the several shafts being caused to dwell in picket-receiving position by movement of said thread-engaging means in the 15 straight portions of the threads.
7. A fence making machine comprising, a plurality of spaced, parallel shafts, a wire twisting head mounted on each of said shafts, means for feeding wires and pickets to said heads, threads 20 formed on said shafts, each of said threads having straight end portions extending longitudinally of a shaft and an intermediate helical portion connecting said straight portions, a carriage movable longitudinally of said shafts, 25 means on said carriage severally engaging the threads on said shafts and power-driven means for imparting reciprocating movement to said carriage to simultaneously turn said shafts, the several shafts being held in picket-receiving position by movement of said thread-engaging means in said straight portions of the threads.
8. A fence making machine comprising, means for feeding pickets longitudinally into the machine, means for feeding and twisting wires between 35 adjacent pickets, means for actuating the pickets away from said twisting means and automatic means for stopping the machine when a picket is improperly fed thereto comprising, a clutch arranged to control said picket feeding and actuating means and wire twisting and feeding means, a toggle joint for controlling said clutch, power-driven, rotary trip mechanism for said toggle joint and means movable by an end of a properly fed picket to render said trip mechanism inoperative.
- 40 9. A fence making machine comprising, means for feeding pickets and wires into the machine, means for twisting wires between pickets, means for actuating the pickets away from said twisting means and automatic means for stopping the machine when a picket is improperly fed thereto comprising, a clutch arranged to control said feeding, twisting and 45 picket-actuating means, means for actuating said clutch, a power-driven, rotary and longitudinally movable shaft and trip mechanism for controlling said clutch-operating mechanism and operable by said shaft, said shaft being disposed in alignment with the pickets and being movable longitudinally thereby to render said trip mechanism inoperative when a picket is properly fed into the machine.
- 50 10. A fence making machine comprising, means for feeding pickets and wires into the machine, means for twisting wires between pickets, means for actuating the pickets away from said twisting means and automatic means for stopping the machine when a picket is improperly fed thereto comprising, a clutch arranged to control said feeding, twisting and 55 picket-actuating means, means for actuating said clutch, a power-driven, rotary and longitudinally movable shaft, trip mechanism for controlling said clutch operating mechanism and

operable by said shaft, and means disposed in the path of the pickets and connected to said shaft for moving the same longitudinally and thereby render said trip mechanism inoperative when a picket is properly fed into the machine.

11. In a machine of the class described the combination with means for feeding pickets into the machine, of means for automatically stopping the machine when a picket is improperly fed thereto comprising, a clutch for controlling the operation of the machine, means for actuating said clutch to stop the machine, a toggle joint arranged to control said clutch operating means, a power-driven shaft mounted for rotary and longitudinal movement, a lug projecting from said shaft, trip mechanism normally extending into the path of said lug to be operated thereby and means connecting said trip mechanism to said toggle joint for disengaging said clutch, said shaft being operable by a picket longitudinally to cause said lug to pass said trip mechanism when a picket is properly fed into the machine.

12. In a machine of the class described the combination with means for feeding pickets into the machine, of means for automatically stopping the machine when a picket is improperly fed thereto comprising, a clutch for controlling the operation of the machine, spring-pressed means for disengaging said clutch to stop the machine, a toggle joint arranged to retain said spring-pressed means in inoperative position, a power-driven shaft mounted for rotary and longitudinal movement, a lug projecting from said shaft, trip mechanism normally extending into the path of said lug, means connecting said trip mechanism to said toggle joint for disengaging said clutch and means operable by a picket and connected to said shaft for moving said shaft longitudinally to cause said lug to pass said trip mechanism when a picket is properly fed into the machine.

13. A fence making machine comprising, means for feeding pickets into the machine, means for feeding and twisting wires between pickets, means for actuating the pickets away from said twisting means, a clutch arranged to be disengaged to stop the machine, a spring tending to disengage said clutch, a toggle joint connected to said clutch and having pivotally joined members adapted to be straightened to retain said clutch in engaged position against said spring and means under control of the pickets for tripping said toggle joint to thereby disengage said clutch at a predetermined point in the cycle of operation.

14. A fence making machine comprising, means for feeding pickets into the machine, means for feeding and twisting wires between pickets, means for actuating the pickets away from said twisting means and means for automatically stopping the machine when a picket is improperly fed into it comprising, a clutch arranged to be disengaged to stop the machine, a spring for actuating said clutch to stop the machine, a toggle joint connected to said clutch and having pivotally joined members arranged to be straightened to retain said clutch in engaged position against said spring, power-driven trip mechanism for said toggle joint and means adapted to be engaged by properly fed pickets to render said trip mechanism inoperative.
